(57) **CLAIM**

The ornamental design for cable connector having interchangeable color bands, as shown and described.

DESCRIPTION

FIG. 1 is an elevation view of the first embodiment of a cable connector having interchangeable color bands, showing my new design;

FIG. 2 is an end elevation view thereof;

FIG. 3 is an end elevation view of the opposite view of FIG. 2;

FIG. 4 is an elevation view of the second embodiment of a cable connector having interchangeable color bands, showing my new design;

FIG. 5 is an end elevation view thereof; and,

FIG. 6 is an end elevation view of the opposite view of FIG. 5.

The stippled portion shown in FIGS. 1 and 4 represent selected colors.

The broken line showing of the environment is for illustrative purposes only and forms no part of the claimed design.
